UNITED STATES PATENT OFFICE.

ADDI BENJAMIN CADMAN, OF BELOIT, WISCONSIN, ASSIGNOR, BY MESNE ASSIGNMENTS, TO WARNER MANUFACTURING COMPANY, OF SOUTH BELOIT, ILLINOIS, A CORPORATION OF WISCONSIN.

CAMPING-VEHICLE.

1,285,930.

Specification of Letters Patent. Patented Nov. 26, 1918.

Application filed January 19, 1917. Serial No. 143,245.

To all whom it may concern:

Be it known that I, ADDI BENJAMIN CADMAN, a citizen of the United States, residing at Beloit, in the county of Rock and State 5 of Wisconsin, have invented certain new and useful Improvements in Camping-Vehicles, of which the following is a specification.

This invention relates to a vehicle which is adapted for camping and like purposes 10 and the invention has particular reference to means for securing beds so that they cannot become accidentally displaced and especially to guard against slippage of the beds during the travel of the vehicle, so as to 15 avoid the great wear which would be caused by such slippage.

In the accompanying drawings, Figure 1 is a side elevation of a vehicle embodying my invention, the beds being shown in position for use. Fig. 2 is a top plan view with the parts in the same position. Fig. 3 is a plan view showing the beds packed for transportation. Fig. 4 is an enlarged transverse sectional view taken in the plane of 25 line 4—4 of Fig. 2. Fig. 5 is a similar view on line 5—5 of Fig. 3.

In the present embodiment of my invention, which constitutes an illustrative example, the vehicle comprises a box-like body 9 30 which is mounted upon a single pair of supporting wheels 10 positioned substantially centrally beneath the body. 11 designates the tongue. Means at opposite ends of the body are provided for supporting such ends 35 directly from the ground when the vehicle is to be used for camping. These means may be the same for both ends and preferably comprise a leg 12 for each corner of the body, the lower end of the leg preferably 40 having an enlarged shoe 13 pivoted thereto to bear upon the ground. In order to level the body of the vehicle in spite of unevenness in the ground, each leg is adjustably connected to the body, the preferred manner 45 of effecting this result being to provide a slot 14 in the upper end of the leg through which a bolt 15 extends, the bolt being seated in a suitable corner piece on the body and being provided on its outer end with a nut 16, 50 having a handle by turning which the leg 12 may be rigidly clamped to the body.

In the preferred form, the body is pro-

vided at the upper edges of its opposite side walls with outwardly extending ledges 17 suitably braced from the side walls. These 55 ledges constitute supports for two beds 18. In the exemplary form shown, each of these beds comprises a rectangular frame which may be filled with any suitable spring material (not shown) and each bed is provided 60 along one side with a suitable number of legs 19, in this instance two, each leg being hinged to the bed so as to be capable of swinging through an arc of approximately 270 degrees to stand in vertical position for 65 supporting the bed, or to lie on top of and parallel to the bed when packed for transportation.

When the beds are set up for use, one side is supported by the legs 19 which are arranged to bear upon the ground, and the opposite side rests upon one of the ledges 17. If desired, the legs may be made adjustable or extensible, in the same manner as the legs 12, to take care of unevenness in the ground. 75 For transportation the beds are packed directly above the body one upon the other. The means for securing the beds in place for preventing displacement or slippage of the beds with relation to each other or to the 80 body comprises separable interlocking devices on the beds and on the body, which devices preferably are in the form of pins and sockets adapted to interengage, but being readily detachable.

In the preferred construction illustrated in the drawings, the pins are provided on the beds and the sockets on the body, although this arrangement might be reversed. Preferably each bed is provided along the side opposite to the side to which the legs 19 are affixed, with downwardly projecting pins 20 of suitable number, two being herein shown. The ledges 17 are provided with complementary sockets adapted to receive these pins on the bed frame. In the present instance each ledge is provided with two sets of sockets 21 and 22 positioned respectively adjacent to the inner and outer edges of the ledge. When the beds are packed for transportation, the pins 20 of the lowermost bed engage in the inner row of sockets 21 on one ledge, and when the beds are set up for use the pins of this lowermost bed are engaged

with the outer row of sockets 22 on the opposite ledge. The exposed space on each of the ledges inward from the bed when set up for use may thus be used as a seat or 5 bench. While this double provision of sockets for the ledges is advantageous and preferable, it is not essential that two sets be provided, but a single set for each ledge might be employed.

10 When the beds are packed one above the other, the pins 20 on the upper bed engage in sockets 23 on the lower bed, the sockets being in the present instance formed in the legs 19 adjacent to their pivot points. The 15 sockets, however, might be otherwise positioned on the bed.

It is advantageous, although not strictly essential, to so construct and arrange the pins and sockets that in packing the beds 20 for transportation either may be placed on the bottom or top, as desired. To this end, the pins and sockets are all made of the same size and the legs 19 of both beds are provided with sockets 23.

25 When the beds are packed they may be bound tightly to the body by any suitable means and the pins and sockets will effectively prevent movement of the beds in a horizontal or edgewise direction either with 30 relation to each other or with reference to the body of the vehicle.

In setting up the beds for use, each bed is moved horizontally edgewise without inversion into position to space the side of the 35 bed carrying the legs 19 away from the body of the vehicle and to engage the pins 20 with the outer sockets 22 at the adjacent side of the vehicle. The pins and sockets securely hold the bed against edgewise or horizontal 40 displacement on the body when in use.

It will be understood that the vehicle is intended to be equipped with a tent which when set up will inclose the vehicle and the extended beds. Inasmuch as the tent structure forms no part of the present invention, 45 I have deemed it unnecessary to illustrate it.

While I have herein shown and described in considerable detail the preferred embodiment of my invention, I recognize that 50 various modifications and equivalent structures will occur to persons skilled in this art. I therefore do not limit myself to the details of the present disclosure. The scope of the invention will be pointed out in the 55 appended claims.

I claim as my invention:

1. A camping vehicle comprising, in combination, a body mounted on a single pair of wheels positioned beneath the mid-portion 60 of the body, means for supporting the opposite ends of the body from the ground, said body having horizontal ledges at opposite sides, each of which is provided with two sets of sockets, one set being near the inner edge of the ledge and the other set

near the outer edge, two bed frames, each having a set of downwardly projecting pins on one side adapted to engage in said sockets and each bed frame having supporting legs hinged to the opposite side thereof and 70 adapted to bear upon the ground, said legs having sockets therein adapted to receive the pins on the superposed bed frame whereby the bed frames may be packed on the body with either frame on top of the other, the 75 pins of the top frame engaging in the sockets of the legs of the lower frame and the pins of the lower frame engaging in the innermost sockets of one of said ledges, the bed frames when set up for use having their 80 pins engaging in the outermost sockets of said ledges, said ledges supporting one side edge of each bed and said legs then occupying an upright position beneath the outer edges of the beds to support the latter from 85 the ground.

2. A camping vehicle comprising a body mounted on a pair of wheels positioned beneath its mid-portion, means for supporting opposite ends of the body from the ground, 90 two beds adapted to be stacked one above the other on the body for transportation, each of said beds comprising a frame and supporting legs hinged to one edge thereof so that the beds are also adapted to be mounted 95 in position for use with one side of each frame supported by the body and the opposite side supported by said legs, the body having a plurality of sockets and the bed frames having pins to engage in said sockets to secure the beds in place and each bed having sockets to receive the pins on the superposed bed for securing the latter.

3. A camping vehicle having, in combination, a body mounted on a single pair of 105 wheels, two beds adapted to be packed on said body for transportation, and further adapted to be supported in position for use with the inner edges of the beds resting upon the body, means for securing the inner edges 110 of the beds to the body, said means being arranged to hold the beds against horizontal displacement but permitting them to be freely lifted bodily out of engagement with the body, legs adapted to bear upon the ground and support the outer edges of the beds, and legs adapted to bear upon the ground and support the body and the inner edges of the beds from tilting movement 115 about the axis of said wheels.

4. A camping vehicle comprising, in combination, a body, two beds adapted to be stacked one on the other on the body for transportation, each bed having legs hinged at one side of the bed whereby the parts are 125 adapted to be placed in position for use with one side of the bed resting on the body and the opposite side supported by said legs, the beds and the body having sockets and pins adapted to interengage whereby either 130

bed may be stacked next to the body with the parts in engagement, the other pins and sockets being adapted to be associated to secure the top bed with relation to the lower bed.

5. A camping vehicle comprising, in combination, a body mounted upon wheels for transportation, and two beds each having legs adapted to coöperate with the body to support the beds in operative position and also adapted to be moved into inoperative position upon the beds to permit the beds to be packed upon the body with the uppermost bed engaging with the legs on the lowermost bed and the lowermost bed engaging with the vehicle body.

6. A camping vehicle comprising, in combination, a body mounted upon wheels for transportation, two beds each having legs adapted to support the beds in operative position and also adapted to be moved into inoperative position upon the beds to permit the beds to be packed upon the body with the uppermost bed resting upon the legs of the lowermost bed and the lowermost bed resting upon the vehicle body, and disengageable devices on the contacting parts for securing the beds against displacement.

7. A camping vehicle comprising, in combination, a body mounted upon wheels for transportation, two beds each having legs adapted to support the beds in operative position and also adapted to be swung into inoperative position on top of the beds to permit the beds to be packed one upon the other in inoperative position on the body, and disengageable devices on the contacting parts for securing the beds against displacement.

8. A camping vehicle having, in combination, a body mounted upon wheels for transportation, a bed having hinged legs adapted to coöperate with the body to support the bed in operative position and also adapted to be swung into inoperative position upon the bed to permit the bed to be packed upon the body, and devices on the contacting parts arranged to hold the bed against horizontal displacement in any direction, but permitting it to be freely withdrawn bodily upwardly out of engagement with the body.

9. A camping vehicle comprising, in combination, a body, two beds adapted to be packed thereon one above the other, each bed comprising supporting legs, disengageable interlocking pins and sockets on the body and the lower bed to prevent slippage of the latter, and disengageable interlocking pins and sockets on the upper bed and the legs of the lower bed to prevent slippage of the upper bed.

10. A camping vehicle comprising, in combination, a box-like body having side

walls, a bed having legs adapted to coöperate with the body to support the bed in operative position and adapted to be moved into inoperative position to permit the bed to be packed upon the body for transportation, said bed being of such width that the opposite edges thereof may be supported by the side walls of the body, and disengageable devices on the bed and body for securing the bed against displacement. 70

11. A camping vehicle comprising, in combination, a box - like body having side walls, a bed having legs adapted to support the bed in operative position and also adapted to be moved into inoperative position upon the bed to permit the bed to be packed upon the body for transportation, ledges on the upper edges of the body side walls adapted to support the opposite edges of the bed when the bed is in inoperative 85 position, and disengageable devices on the bed and body for securing the bed against displacement.

12. A camping vehicle comprising, in combination, a box-like body having side walls, two beds having legs adapted to coöperate with the body to support the beds in operative position and also adapted to be moved into inoperative position to permit the beds to be packed one upon the other upon the body for transportation, ledges on the upper edges of the body side walls for supporting the inner edges of the beds when in operative position and for supporting the opposite edges of the lower- 100 most bed when in inoperative position, and disengageable devices on the beds and body for securing the beds against displacement.

13. A camping vehicle comprising in combination, a body, a bed having supporting legs hinged to one side thereof, the bed being adapted to be positioned directly above the body when traveling and being adapted to be moved edgewise horizontally without inversion into position for use, in which position said supporting legs will bear upon the ground and the other side of the bed will be supported by the body, separable interengaging devices comprising complementary pins and sockets on the bed and the body, 115 said devices on the bed being located at the side opposite to said supporting legs, and the complementary devices on the body being located at opposite sides thereof to coöperate with the devices on the bed when the latter 120 is in position either for transportation or for use.

14. A camping vehicle comprising, in combination, a body, two beds, each having supporting legs at one side thereof, the beds 125 being adapted to be packed one upon the other directly above the body for transportation and being further adapted to be moved from said position edgewise horizontally without inversion into position for said sup- 130

porting legs to bear upon the ground and the opposite side of each bed to be supported by the body, and separable interengaging pins and sockets on the beds and the body adapted to secure the beds against slippage in either position.

15. A camping vehicle comprising, in combination, a body, a bed having rigid downwardly projecting pins along one side and 10 having supporting legs along the opposite side, said body being adapted to support the first mentioned side of the bed when in use and being provided with complementary sockets to receive said pins.

15 16. A camping vehicle comprising, in combination, a body, a bed having supporting legs at one side thereof and having projections at its other side and said body having two sets of sockets along its opposite sides, 20 either of which sets is adapted to receive

said projections for securing the bed either in position for transportation or for use.

17. A camping vehicle comprising, in combination, a body, two beds each having supporting legs along one side thereof adapted to support such side from the ground, the opposite side of each bed being adapted to be supported by the body and being provided with downwardly projecting pins, the body having sets of sockets at its opposite sides adapted to receive said pins, and the two beds being adapted to be packed directly above the body one upon the other with the pins of the lower bed engaging in sockets at the opposite side of the body from those in which such pins engage when the bed is set up for use.

In testimony whereof, I have hereunto set my hand.

ADDI BENJAMIN CADMAN.
